UNITED STATES PATENT OFFICE.

FRANK W. ROBINSON, OF READING, PENNSYLVANIA, ASSIGNOR TO THE NOLDE & HORST CO., OF READING, PENNSYLVANIA, A CORPORATION OF PENNSYLVANIA.

TUCKING MECHANISM FOR KNITTING MACHINES.

1,425,288.

Specification of Letters Patent. Patented Aug. 8, 1922.

Application filed April 24, 1919. Serial No. 292,262.

To all whom it may concern:

Be it known that I, FRANK W. ROBINSON, a citizen of the United States, residing at the city of Reading, in the county of Berks 5 and State of Pennsylvania, have invented certain new and useful Improvements in Tucking Mechanism for Knitting Machines, of which the following is a specification.

My invention relates to circular knitting machines, and my object is to provide improved means for intermittently effecting a tucking action of determined needles of the knitting series as may be required to produce various desired effects.

Such tucking action is commonly effected by providing determined needles with relatively long latches, which require a greater latch-clearing movement of such needles for ordinary knitting than is required for the needles having ordinary latches; successive loops being otherwise retained upon such relatively long latched needles so as to produce the tucking effect. My improved construction provides for producing such effects as desired in a very simple manner involving no variation of the needle butts upon which the knitting cam mechanism operates; as fully described in connection with the accompanying drawings illustrating my invention; the novel features of which are clearly defined in the claim.

Fig. 1 is a plan view showing a knitting cam mechanism including my improvements, in connection with a rotatable needle cylinder shown in partial horizontal section and provided with both long and short butt needles.

Fig. 2 is a diagrammatic view showing knitting cams with my tucking cam in preferred relation thereto, and indicating different courses of the needles as hereinafter described.

Figs. 3 and 4 indicate respectively a needle having an ordinary latch, and a longer-latched needle which is employed as set forth both for ordinary knitting and for tucking.

The circular series of needles indicated is divided as usual into long-butt and short-butt groups, the former of which are raised out of action during reciprocative knitting. All of the needles that are in action are operated by the usual top center cam 5 and latch-clearing cams 6 and 7 to impart there-

to the vertical movements normally required to successively form loops thereon and clear the same from their latches as in ordinary circular or reciprocating knitting.

In my improved construction the special long latch needles (Fig. 4) may be employed instead of ordinary latch needles (Fig. 3) in either the long or short butt groups, wherever it is desired to produce tucking effects; the required operation of these needles for either ordinary knitting or tucking being provided for by the special cam hereinafter described irrespective of the length of the butts with which the needles are provided.

This special needle operating or tucking cam 10, as shown, is provided with a radially projecting shank 11 which is movably mounted in guide-ways 12, 12, and is normally projected toward the needle cylinder 13 by a spring 14. The line of projection is such as to bring the cam 10 into contact with the radially extending needle butts of either the long or short butt needles that have been normally raised by the latch-clearing cam 6; so that said cam will have no effect when brought into contact with long butts 20 until after the passage of the latter, but will then be further projected by the spring 14 into contact with the short butts 21 (the position shown in Fig. 1) so as to lie under the returning long butts. When in this partially projected position, indicated in Fig. 1, the cam 10 is adapted to raise all the long butt needles beyond the usual latch-clearing elevation imparted to them in riding upward

upon the cam 6; and is at the same time fully projected by the constantly pressing spring 14 so as to position it under the short butts 21 and thereby effect a similar raising of all the returning short butt needles. The effect of this normal spring-pressed movement of the special tucking cam 10 is, therefore, to raise all the needles beyond the normal lift imparted by the usual latch-clearing cam 6, which excess lift is sufficient to make the long latch needles as well as the others clear their loops for ordinary knitting.

When it is desired that said long latch needles shall operate to produce a tucking effect, it is only necessary to entirely withdraw from action said tucking cam 10, so that only the ordinary latch-clearing movements will be imparted to all the needles by the ordinary cam 6; which latch-clearing

movements are insufficient to clear the loops from the long latch needles until the supplemental tucking cam is again thrown into action.

- 5 The withdrawal movement of the tucking cam 10 positively effected when desired, by means of a bell-crank lever 25 as indicated, to which required movements may be imparted through a connecting rod 26, by well known cam or pattern-control mechanism commonly employed; the projecting movements however being freely effected by the spring 14 excepting as limited by contact of the cam 10 with the extending butts of the passing needles as has been described. As shown in the drawing the point 27 of the usual latch-clearing cam 6 is slightly blunted, and the projected tucking cam 10 is adapted to periodically form a similarly inclined extension of said cam upon which the needles are further raised to make the long-latch needles operative for ordinary knitting.
- 20 In Fig. 2 the ordinary course of all the needle butts, over the cam 6 commonly employed, is indicated by the dotted line 30; such course being followed when the supplemental or so-called tucking cam 10 is periodically withdrawn from action so as to leave any long latch or tucking needles without sufficient movement to clear their loops. When the tucking cam 10 is released to the action of its projecting spring 14, it may first be stopped temporarily by contacting with the long needle butts passing over the cam 6; but after their passage it is automatically projected further until stopped by contact with the shorter needle butts as shown in Fig. 1, which places it under the

ends of the returning long butts, where it 40 is free to be fully projected automatically into the plane of the cam 6 so as to form an upward extension of the latter. When in this position all the needle butts ride over it, in the course indicated by the heavier 45 dotted line 31, thus causing the long-latch needles to clear their loops and operate with the others for ordinary knitting until the cam 10 is withdrawn as determined by the operation of the withdrawing lever or bell 50 crank 25.

The periodic actions thus provided for affect all the long-latch needles similarly, but may be varied in time and extent as desired for different effects and purposes;—the use of my invention in connection with the omission of adjacent needles to produce drop stitches, for instance, enabling the production of attractive lace effects.

What I claim is:—

In a knitting machine comprising series of long butt and of short butt needles, certain of which are provided with relatively long latches; knitting cams including a two-part latch-clearing cam comprising a fixed part operative upon all the needles sufficiently only to clear the loops of the short-latch needles and a movable tucking-cam top-extension part normally spring-pressed toward the needles and adapted to automatically position under the butts of the latter for increasing the latch-clearing movements imparted thereto; and intermittently operated means for positively withdrawing said tucking cam extension.

In testimony whereof I affix my signature.

FRANK W. ROBINSON.
